UNITED STATES PATENT OFFICE

FERDINAND SOUCZEK, OF REICHENBERG, CZECHOSLOVAKIA

SHUTTLE FOR LOOMS

Application filed July 20, 1927, Serial No. 207,301, and in Czechoslovakia July 26, 1926.

In looms of this kind the wooden shuttle is built as a hollow body, in the inside of which the weft bobbin is set on a spindle and arranged in such manner that its longitudinal 5 axis coincides with that of the shuttle.

The peculiarity of looms with friction drive shuttles is that when the loom is shut off, the shuttle remains in the shuttle box even when the loom continues to make a few 10 no load revolutions, and this fact admits of the use of a shuttle such as is the object of the present invention. The latter consists in the weft bobbin being set outside the shuttle which is a simple prismatic wooden rail.

15 In the accompanying drawings an application of the invention is shown, whereby

Fig. 1 shows the shuttle viewed from the front,

Fig. 2 from the side and

20 Fig. 3 from above,

Fig. 4 shows a horizontal section of the shuttle spindle,

Fig. 5 a perpendicular section of the weft 25 bobbin shell with thread eye,

Figs. 6 and 7 a device for securing the weft bobbin to the shuttle,

Fig. 8 the shuttle box in profile and

Fig. 9 another embodiment of the fastening of the weft bobbin.

30 Weft bobbin spindle 1 in Fig. 4 is bent at right angles at its heavy end and provided with an indentation 2 and a cone-shaped point 3. Just in front of the bending and soldered to the spindle 1 is a funnel-shaped 35 piece 4 of sheet metal carrying on its cylindrical part the stud 5. The weft bobbin can be set in the usual manner on the spindle, whereby the rectangularly bent end of the latter is an excellent means of preventing any 40 turning and the end of the bobbin can be inserted in the tube section 4. The diameter of the weft bobbin must, of course, be a little less than the internal diameter of said tube section. After inserting the bobbin, the shell 6 45 is shoved over it. The shell 6 comprises a

thin preferably cylindrical tube with one end of gradually decreasing diameter terminating in a thread eye 7, the opposite end being fully open except for a slightly contracted free edge. This shell yields at its open end 50 by means of the slit 8 and can, accordingly, be pushed over the tube section 4, whereby stud 5 is inserted in recess 9 of slit 8, thus securing the shell from turning or being shoved further in. At the same time the 55 drawn in edge of the shell by means of its spring action prevents the two parts from becoming involuntarily shoved apart. At the pointed extremity of the shell 6 in the prolongation of the slot 8 a stud 10 is secured 60 which is of the same shape as the bent end of spindle 1. A thread eye 11 is further located opposite this last mentioned stud.

It is clear that before inserting the shell the weft thread must first be drawn through it as 65 well as through thread eye 7, in order to be passed through thread eye 11 later on. In order to brake the weft it is a good thing to paste over the cone-shaped end of the shell 70 with velvet or the like.

The shuttle 12 consists of a wooden rail or bar, pointed at both ends and terminating in an iron point or sheet metal holder. The fastening of the shell 4-6 containing the weft bobbin, to the shuttle is effected by inserting the two pins 1, 2, 3, and 10 of the weft bobbin or cartridge in the bushings 13 (Fig. 6) provided therein at suitable positions, as appears plainly in Fig. 3. In order to prevent the weft cartridge from working 75 loose in the shuttle, the bushings 13 are provided with cross slits and the shuttle is provided with a groove 14 in which a steel wire 80 15 which has been previously slightly bent is inserted, said wire being tightened and held fast by stud 16 so that the ends of this steel wire fall into the slits of the bushings. On introducing the studs of the weft cartridge into the bushings 13 of the shuttle their cone-shaped ends first force spring 15 out of the 85 90

bushings 13 of the shuttle, said spring as soon as the weft cartridge has been entirely introduced into the shuttle, falling into the notches 2 of the studs and thus preventing 5 the weft cartridge from falling out of the shuttle.

Another embodiment of the fastening of the weft cartridge to the shuttle is shown in Fig. 9. In this case the end of spindle 1 is 10 not curved, but projects in its extended part a little out of the tube section 4. On the other side of the weft cartridge the thread eye is prolonged to form a bushing so that the weft cartridge terminates at both ends in pins 19 which serve for fastening to the shuttle. In 15 place of the bushings 13 the shuttle is provided with spring clips 20 secured thereon by riveting 21 in such manner that the distance between the two clips is equal to that between the pins of the cartridge. As is evident 20 from Fig. 9 the weft cartridge with its pins 19 is pressed in between these clips.

The shuttle is driven in the usual manner by means of a gripping flange, the shuttle being 25 also provided in this event on its longitudinal sides with wedge-shaped slanting surfaces which serve as interlocking surfaces for engaging the gripping flange 17 (Fig. 7).

The shuttle box 18, as shown in Fig. 8, is 30 built in such manner that it is provided with a longitudinal slit on the front wall and only receives the real shuttle 12, whereas it leaves the weft cartridge free by means of the slot like open front wall of the shuttle box.

The weaving operation is now as follows: 35 The weaver receives either two weft cartridges of which one is always running in the loom while he fills the other himself or he is continually given charged cartridges. The loom always works with one and the same 40 shuttle which never need be taken out. When the weft bobbin is exhausted and the loom accordingly stopped, the shuttle still remains in the shuttle box in the case of looms with friction drive of the shuttle as was already 45 mentioned at the beginning. All that the weaver now has to do is to pull out in the direction of the arrow the conveniently accessible weft cartridge (Figs. 8 and 9) and to insert a fresh, charged cartridge into the 50 shuttle, whereof the thread end is already fastened to the edge of the cloth.

It is, of course, only natural that this device 55 greatly accelerates and facilitates the changing of the weft bobbins. Other advantages are that much more yarn can be carried with the same sized shed opening and that further the weight of the shuttle with weft cartridge is less than formerly. The 60 friction on the warp threads is considerably reduced as a result of the smooth weft cartridge and contact between the weft thread running off the weft bobbin and forming a spherical mass with the warp is also completely avoided, so that consequently warp 65

and weft thread breakages are much less common. In addition to the above the construction of looms with friction drive shuttles is greatly simplified by the use of the above described shuttle.

It is further remarked that the weft cartridge may just as well be made of celluloid or the like instead of sheet metal, or in other words transparent so that the weft bobbin may be visible while running, and in like manner the plate of the weft cartridge may be perforated or slotted for the same purpose.

Attention is further called to the fact that it is entirely immaterial as far as the principle of the invention is involved as to whether the protective shell instead of in the manner described above in connection with the example taken by way of illustration is made perpendicularly removable (liftable) from the shuttle board or secured by laterally pushing on, and that further the manner in which the two-part shell is put together is of secondary importance.

Having now more fully described and ascertained the nature of my invention and in what manner the same is to be performed, I declare that what I claim is:

1. A shuttle body and a bobbin carrier secured exteriorly of the shuttle body, said carrier including telescopically related sections capable of separation to provide for the introduction of the bobbin.

2. A shuttle body and a bobbin carrier secured exteriorly of the shuttle body, said carrier including telescopically related sections capable of separation to provide for the introduction of the bobbin, and means carried by one of the sections to receive and support the bobbin.

3. A shuttle body, a bobbin carrier made up of hollow sections adapted for interconnection, and means carried by the respective sections for securing the carrier as a whole to and in a position exteriorly of the shuttle body.

4. A shuttle body, a bobbin carrier including shell-like sections adapted for interconnection to enclose a bobbin, a bobbin receiving spindle carried by one section, the remaining section being formed with a thread eye, and projections from the respective sections to removably cooperate with the shuttle body to support the carrier wholly exteriorly of the shuttle body.

5. A shuttle body and a bobbin-enclosing carrier frictionally secured to the body to permit ready detachment of the carrier.

6. A shuttle body and a bobbin-enclosing carrier, and cooperating connections on the carrier and body to permit the carrier to be connected to and disconnected from the body by suitable pressure on the carrier.

7. A shuttle body, a bobbin-enclosing carrier, projections on the carrier, and spring

elements on the body to removably receive and frictionally grip said projections, whereby to facilitate speedy removal or replacement of the carrier relative to the body.

8. A shuttle body, a carrier in which the bobbin is completely enclosed, and cooperating interlocking elements on the body and carrier for connecting said body and carrier to permit carrier and contained bobbin to be applied to the body through pressure on the carrier.

In testimony whereof I affix my signature.
FERDINAND SOUCZEK.
